UNITED STATES PATENT OFFICE.

GEORGE W. BUCHANAN, OF CHICAGO, ILLINOIS.

CUFF-HOLDER.

SPECIFICATION forming part of Letters Patent No. 772,210, dated October 11, 1904.

Application filed May 12, 1902. Serial No. 107,029. (No model.)

To all whom it may concern:

Be it known that I, GEORGE W. BUCHANAN, a citizen of the United States, residing at Chicago, county of Cook, State of Illinois, have 5 invented a certain new and useful Improvement in Cuff-Holders; and I declare the following to be a full, clear, and exact description of the invention, such as will enable others skilled in the art to which it pertains to make 10 and use the same, reference being had to the accompanying drawings, which form a part of this specification.

My invention has for its object the production of a cuff-holder of that form in which two 15 buttons such as are generally known as "collar" or "stud" buttons are engaged together, the base of one button being provided with means for engaging the head of the other. The improvement sought to be covered by 20 this application is the means for engaging the two buttons together.

In the drawings, Figure 1 is a vertical section of the upper button—that is, the button that is engaged in the cuff when the device is 25 used as a cuff-holder. Fig. 2 is a plan view of the base-cap with the balance of the button removed, and Fig. 3 is a vertical section of the two buttons engaged together.

In carrying out the invention, A represents 30 the upper button—that is, the one engaged in the cuff when the device is used as a cuff-holder, although obviously it is adapted for other purposes. This button is provided with a top or head α , a shank α' , and a base α'' .

B is the lower button—that is, the one engaged in the wristband of the shirt when used as a cuff-holder. It is provided with a head b , a shank b' , and a base b'' . Either or both the buttons may be what are technically 40 termed "one-piece" buttons, or they may be of other constructions. This is immaterial.

C is a plate or ring engaged to the base α'' of the button A by either crimping the edge c around the edges of the base or by any other 45 method.

c' represents spring-detents formed integral with the plate C and so bent that they extend inwardly or toward the base, leaving an ori-

fice D, into which the head b of the other button may be inserted. The pressure of the 50 detents c' on the head serves to hold the head b detachably engaged to the base of the button A, while the buttons remain to all outward appearances similar to the buttons now in use without projecting parts, which are 55 cumbersome, unsightly, and unfinished in appearance.

Each button, as will be seen, when separated from the other has its own head, shank, and base, so that each can perform its respective 60 function of holding the cuff or wristband together, as the case may be, and yet when engaged together they combined form an effective and easily-detached cuff-holder.

I do not herein claim the generic invention 65 shown in this application and in my Reissue Patent No. 12,020; but what I do claim in this application is the specific embodiment of the generic invention which is disclosed herein. 70

What I claim is—

1. The combination with a stud-button comprising a head, a shank and base, of a circular plate having a concentric hole therethrough and having a flange at its upper edge overlying and closely engaging the outer periphery of said base, thereby permanently uniting the plate to the stud-button, and a series of spring-detents within the space between said base and plate and located around the hole through said 75 plate. 80

2. The combination with a stud-button comprising a head, shank and base, of a circular plate having a flange at its upper edge overlying and closely engaging the outer periphery of said base and thereby permanently uniting the plate to the stud-button, and a series of integral spring-detents extending from the lower edge of said plate upwardly within the same. 85 90

In testimony whereof I sign this specification in the presence of two witnesses.

GEORGE W. BUCHANAN.
